William Weston,

UNITED STATES PATENT OFFICE.

SALISBURY F. ROSSE, OF SEDALIA, MISSOURI.

CAR-DOOR FASTENING.

SPECIFICATION forming part of Letters Patent No. 291,404, dated January 1, 1884

Application filed August 6, 1883. (Model.)

To all whom it may concern:

Be it known that I, SALISBURY FRANCIS ROSSE, a citizen of the United States, residing at Sedalia, in the county of Pettis and State 5 of Missouri, have invented certain new and useful Improvements in Car-Door Locks, of which the following is a description.

My invention relates to fastenings for car-doors; and it consists in the improved construction and combinations of parts hereinafter 10 described, whereby the doors may be readily and securely fastened, a seal-connection applied thereto, and the entire fastening disconnected to permit the movement of the door, 15 the construction and relative arrangement of the door and lock being such that when the latter is attached to the side of the car in the direction of the movement of the door it in no manner interferes with such movement of 20 said door.

In the accompanying drawings, Figure 1 is a side elevation of a section of the side of a car having my improvements applied thereto. Fig. 2 is a plan view of the peculiar form of 25 latch employed in carrying out my invention, the said latch being in a horizontal position. Fig. 3 is a front view of Fig. 2, and Fig. 4 is a front end view of the improved latch.

A bar, *a*, secured to the side *A* of the car, 30 above the door-opening thereof, has hung thereto by suitable straps or hangers, *b*, a door, *B*. The movement of the door *B* in the direction necessary to cover the door-opening is limited by means of a vertical bar, *c*, which is 35 secured to the side of the car by any suitable means, and at the side of the door-opening. The bar *a* is of such length as to permit the movement of the door thereon sufficient to expose the entire door-opening. A keeper, *P*, 40 is secured to the side of the car beneath the lower corner, *h*, of the door, and is bent or shouldered, so as to pass beneath the lower side of the door and project up for a short distance in front of the lower corner edge, *h*, of the door. 45 On the side *A* of the car, and in front of the lower edge of the door, is pivoted a latch, *C*. The latch *C* is bent or angled, so as to form three portions—a portion, *i*, which bears 50 against the side *A* of the car, and is pivoted thereto by means of a pin or pivot, *m*, passing through a perforation, *g*, therefor in said por-

tion *i*; a portion, *j*, which is bent out at right angles from the portion *i* of the latch, and transverse to the direction of travel of the door, and a portion, *k*, bent parallel with the 55 side *A* of the car, but in a direction opposite to that in which the portion *i* extends. The lower part of the portion *k* is bent out at an angle to the rest of the same, so as to constitute a lip, *d*, and the upper corner *e* of the 60 said portion is bent up, so as to form an ear, which has a perforation, *n*. When the latch *C* is in a dependent position, as shown in dotted lines, Fig. 1, the angle portion *j* is below the bottom edge of the door, which is hung on 65 the bar *a*, so as to leave sufficient space between the exterior of the car-side *A* and the inner side of the door *B* for the portion *i* of the latch to pass between, so that said latch while being pivoted and located in the direction of the movement of the door *B* does not 70 in any way interfere with such movement. When the door *B* is moved so as to close the door-opening, the latch *C* is swung around, as indicated by the arrows, Fig. 1, so that when 75 it occupies the position illustrated by the full lines in said figure the lip *d* of said catch will bear against the inner side of the shouldered keeper *P*, and force the rear face of the portion *k* of the latch against the door, thereby 80 clamping the door in its closed position, the portion *j* of the latch being located transversely across the front edge of the door *B*, and preventing any longitudinal movement thereof. A seal-fastening, *q*, may then be applied to 85 the lock by passing the wire thereof through a staple, *f*, secured to the side of the door *B*, in close proximity to the ear *e* of the portion *k*, and through the perforation *n* of said ear.

From the foregoing description it will be apparent that the fastening devices constructed and operating as described render the secure fastening of car-doors attainable with but little difficulty or effort, and that the fastening devices themselves are of simple and cheap production and application, and of durable construction.

I claim—

1. As a new article of manufacture, a latch for cars, consisting of the portions *i j k*, the portion *i* being perforated for the pivotal attachment of the latch to the car-side, the por-

tion *j* constituting a shoulder, and the portion *k* having a lip, *d*, at its lower edge, and a perforated ear, *e*, at or near its upper forward corner, substantially as set forth.

5 2. The combination, in a car, of a door having a staple on its outer side, a keeper projecting from the side of the car, a latch pivoted to the side of the car and provided with a lip and perforated ear, and adapted to be moved to a position to cause its lip to bear against the keeper, and thereby wedge the door in its closed position, and a seal-connection, *q*, for connecting the staple with the perforated ear of the latch, substantially as described.

10 3. The combination, in a car, of a sliding door, a keeper projecting from the side of the car, a latch pivoted to the side of the car, and having a portion, *i*, adapted, when the door is unlatched and moved, to pass between the

door and the side of the car, and with a shoulder and lip, the former adapted, when the latch rests within the keeper, to be arranged transversely across the front edge of the door, and prevent its longitudinal movement, while the lip bears against the keeper and wedges or clamps the door against the side of the car, substantially as set forth.

15 4. The combination, in a car, of a sliding door, *B*, having a staple, *f*, keeper *P*, projecting from the side of the car, a shouldered latch, *C*, pivoted to the side of the car and consisting of the portions *i j k*, and having a lip, *d*, and perforated ear *e*, all arranged and operating substantially as herein set forth.

SALISBURY F. ROSSE.
